CHILD'S DEVELOPMENT GAME

Ora B. Griffin, Vashon, Wash.

Application April 20, 1948, Serial No. 22,219

2 Claims. (Cl. 35—1)

1

This invention relates to the general art of games and more particularly, to a child's development game.

A large number of games have been created for the entertainment and instruction of children. Very often, however, these games have been created with the prime object of amusing the child. While this has some virtue, in that it will keep a child busy and thus free the mother for other useful work, it is believed most desirable to have children's games definitely in keeping with their age group and, in addition to amusing and time-consuming features, they should have a definite plan for development of the child.

My present game is of this latter type, and is intended for pre-school children, to give them first-hand instruction in the following of simple rules. Secondly, it is to teach color perception and finally, it teaches aptitude, which is generally considered one of the accomplishments which will most greatly assist children in assimilating instruction as they enter kindergarten or the first grade of school.

The principal object of my present invention, therefore, is to provide a development game.

A further object of my invention is to provide a game that gives ample opportunity for the distinguishing and perception of color.

A further object of my invention is to assist in the development of aptitude.

Further objects, advantages and capabilities will be apparent from the description and disclosure in the drawings or may be comprehended or are inherent in the device.

In the drawings,

Fig. 1 is a face view of the various playing elements making up my game.

Fig. 2 is a perspective view, showing a center section and one petal member of my game to illustrate the general relationship desirable between size and depth.

Fig. 3 illustrates the arrangement of my game pieces on a plane surface, it being viewed as though four players were playing, or two players, each playing two colors.

My game, while it might be considered as being capable of extension into other colors, normally consists of four daisy centers 10. These centers, in keeping with all of my game playing elements, have a common finish for one side, so that when the pieces are all turned with the reverse side uppermost, they will all be the same finish and it will be impossible to distinguish or determine by inspection what color will be shown on the reverse side.

Adapted for final matching up with centers 10 are a plurality of petal members 12. These members are of preferably the same color as the centers, so that when a daisy is finally formed, the center and petals will all be of the same color.

In Fig. 3, I have indicated, by section lining, four different colors. I do not wish to be limited to these four colors and have shown these particular colors only as representative of my game planning.

As my game lends itself to the testing of a child's mental development, I have found that steps should be taken to insure fairness and the comparative progress of children who may be tested. It has been observed that many times a child may see the edge of the color coating, if the coloring extends to the extreme edge of the petals, even when the colored side is turned down. To overcome this condition, I provide an uncolored margin 14 around the periphery of each petal.

While it is possible for the players to make certain local rules of their own as variations, the instructive value of the game is best obtained when the game is played according to the following rules:

This game, as illustrated, consists of four centers and twenty-four petals. The four round daisy centers are shuffled and placed in a pile upside down. The various colored petals are also shuffled and placed in a pile upside down. Each player chooses a center. If there are only two players, each player can choose two centers; if there are three players, one center is laid aside. Players place centers in front of them on the table, then taking turns, each player draws a petal from pile, or from top of pile. If it matches the color of his center he places it next to center. If otherwise, the player starts another pile, placing the petal upside down; players keep on taking turns drawing petals from center pile until it is all gone. If no one has obtained five petals alike, they start drawing from the second pile until one player has finished his daisy. As soon as the player has all six petals, he calls out "It's a daisy" and wins the game.

If two players use two centers apiece, the first one to get both daisies finished wins.

It is believed that it will be clearly apparent from the above description and the disclosure in the drawings that the invention comprehends a novel child's development game.

Having thus disclosed the invention, I claim:

1. A child's development game consisting of: 55 a plurality of circular flower centers each having

a type of back surface common to all and a colored front surface contrastingly different from each of the other flower centers; a plurality of groups of flower petals each of identical form and having a concave arcuate end so proportioned that a group of petals will completely form a tight encirclement of a flower center; each of said petals having a type of back surface common to all the petals of the game and a front surface which for all the petals of one group are colored to match the colored front surface of their companion flower center and a type of vertical edge entirely around said petals which is common to all the petals of the game.

2. A child's development game consisting of: a plurality of flower centers each having a type of back surface common to all and a colored front surface contrastingly different from each of the other flower centers; a plurality of groups of flower petals each of identical form and hav-

ing an end so proportioned that a group of petals will co-act to form a tight encirclement of a flower center; each of said petals having a type of back surface common to all the petals of the game and a front surface which for all the petals of the game and a front surface which for all the petals of one group are colored to match the colored front surface of their companion flower center and a type of vertical edge entirely around said petals which is common to all the petals of the game.

ORA B. GRIFFIN.
